UNITED STATES PATENT OFFICE.

JOHN H. GEIER, OF GALION, OHIO.

ADJUSTABLE SOLE-PATTERN.

1,239,475.

Specification of Letters Patent. Patented Sept. 11, 1917.

Application filed February 1, 1917. Serial No. 146,044.

To all whom it may concern:

Be it known that I, JOHN H. GEIER, a citizen of the United States, and a resident of Galion, in the county of Crawford and State of Ohio, have invented a certain new and useful Adjustable Sole-Pattern; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to a sole pattern which is adjustable to adapt it to fit closely around the edges of soles of different shapes and sizes and is capable of being secured in any form to which adjusted to serve 20 as a pattern for cutting duplicate soles.

The object of my invention is the provision of a pattern of the class described, which is capable of being easily and quickly adjusted to the shape and size of a sole of 25 which a pattern or duplicate is desired, and is also light, simple and inexpensive in its construction.

The invention is fully described in the following specification, and while, in its broader aspect, it is capable of embodiment in numerous forms, a preferred embodiment thereof is illustrated in the accompanying drawings, in which—

35 Figure 1 is a perspective view of a pattern embodying the invention. Fig. 2 is a plan view thereof. Fig. 3 is a reduced plan view of the pattern opened up with the securing bolts and locking lever removed, and Fig. 4 is an enlarged section on the line 4—4 in Fig. 1.

Referring to the drawings, 1 designates the rim member of the pattern, which is composed of a plurality of sections, preferably of sheet metal, of an easily pliant or 45 flexible nature. These rim sections, in the present instance, comprise the two front sections *a* and *b* and the two opposed rear sections *c* and *d*, the front sections having their adjacent ends connected for sliding 50 longitudinal adjustment by the provision of longitudinally extending slots 2 in the forward end portion of the section *b*, in the present instance, through which rivets or bolt members 3, which are fixed to the forward end of the front section *a*, project for 55 free sliding movements therein in the man-

ner indicated in Fig. 4. Each rear section *c*, *d* is provided in its forward end with a pair of transversely spaced longitudinally extending slots 4 and is adjustably secured 60 to the rear ends of the respective front sections by rivets or bolt members 5, which project therefrom through the registering slots 4.

The pattern is provided interiorly of the 65 rim 1 with a plurality of plates, one being provided for and carried by each section of the rim, and these plates are connected together in a manner to permit an easy and rapid relative adjustment of the rim sections 70 to suit the size and shape of a sole to which the pattern may be fitted. The plates which are carried by the rim sections *a* and *b* are designated 6 and 7, respectively, the former having one portion attached to the section *a* 75 intermediate its ends, as at 8, and having its end portions attached to the respective ends of the section *a* through the medium of the respective rivets 3 and 5 at the inner sides of the respective ends of the rim sections *b* and *d*, as shown. The section 7 has one end fixedly attached to the forward end portion of the section *b* at the rear of the slots 2 therein, as at 9, and has its rear end connected to the rear end of the section *b* by the adjacent rivets 5 at the inner side of the section *c*. The plates 10 and 11, which are carried by the rear sections *c* and *d*, respectively, are each fixed at spaced points to said sections, as indicated, said plates retaining the 85 rear end portions of the respective sections *c*, *d* in desired curved form, as best shown in Fig. 2.

The plates 6 and 7 are adjustably retained together in lapped position at their 95 forward ends by a bolt 12, which passes through an aperture 13 in the plate 6 and a transversely extending slot 14 in the plate 7, thus permitting a broadening or narrowing 100 adjustment of the front sections *a* and *b* of the rim. The sections 10 and 11 are intended to lap each other and have extensions 115 at their forward ends, which, in the present instance, lap under the rear end portions of the lapped plates 6 and 7 and have elongated diagonally disposed slots 16 there- 105 in which cross each other at an acute angle when the plates 10 and 11 are lapped, as shown in Fig. 2. The rear ends of the several plates are secured together in lapped 110 relation by a bolt 17, which projects through an aperture 18 in the top plate 6, thence

through a transversely elongated slot 19 in the rear end portion of the plate 7, and thence through the slots 16, 16 in the lapped plates 10 and 11 at the point of intersection of said slots. The rear ends of the plates 10 and 11 are connected together in lapped relation by a bolt 20, which projects through an aperture 21 in the plate 11 and a transversely disposed slot 22 in the plate 10. The several bolts or connecting members 12, 17 and 20 are sufficiently loose to permit a free relative sliding adjustment of the plates respectively connected thereby.

23 designates a locking lever which is pivoted to the rear end of the plate 6, as at 24, and has its forward end provided with a cross-head 25 having a segmental slot 26 therein through which the bolt or plate connecting member 17 loosely projects. The cross-head 25 is tapered or gradually thickened longitudinally thereof from both ends to adapt it to act as a cam for coöperating with the head of the bolt 17 to lock the plates in adjusted position when the lever 23 is moved to place the thickened portion of its head in wedge engagement with the bolt head.

It will be noted that the plates 6, 7, 10 and 11 are secured to the respective rim sections in spaced relation to at least one edge thereof so as to permit an edge of the rim to project transversely from the plates and form a flange for fitting around the edge of a sole of which it is desired to take a pattern.

In the use of my pattern an edge of the rim 1 is fitted around the sole of which a duplicate is to be cut, the lever 23 having first been moved to released position and the rim sections *a*, *b*, *c* and *d* having been expanded and longitudinally adjusted to a size suitable to permit a reception of the sole within the rim. When the pattern rim has been placed around the edge of a sole the sections of the rim are relatively adjusted in whatever manner may be desired to cause the several sections to fit closely to the portion of the sole with which they coact, so that the rim, when removed from the sole, will form a true pattern of the same for cutting a duplicate sole. When the desired adjustment of the rim sections has been accomplished the lever 23 is moved to locking position to retain the sections in adjusted position. Upon a lengthening of the rim by a rearward longitudinal movement of the sections *c*, *d* with respect to the sections *a*, *b*, the bolt 17, in coöperation with the diagonally crossing slots 16, 16 of the plates 10 and 11, will cause a gradual broadening of the rim in correspondence with the lengthening of the same, such broadening being permitted by reason of the bolts 17 and 20 passing through the transversely disposed slots 19 and 22 in the plates 7 and 10, respectively.

A broadening of the toe portion of the rim may also be effected by reason of the adjusting connection provided between the forward ends of the rim sections *a* and *b* and the transverse slot 14 through which the bolt 12 projects.

It is thus evident that the provision of the flexible adjustably connected sections of the rim and the plates 6, 7, 10 and 11 with the pin-and-slot connection therebetween enables the rim of the pattern to be easily and quickly adjusted both as to width and length and also as to shape to suit the form of the sole of which a pattern is being taken.

I wish it understood that my invention is not limited to any specific construction, arrangement or form of the parts, except in so far as such limitations are specified in the claims.

Having thus described my invention, what I claim as new, and desire to secure by Letters Patent, is—

1. A sole pattern having a rim formed of a plurality of pliant sections, separate means slidingly connecting the adjacent ends of the rim sections for relative longitudinal adjustment, and means disposed interiorly of said rim and operable to permit an adjustment of the rim and its sections and to secure the same in adjusted relation.

2. A sole pattern having a rim formed of a plurality of pliant sections, separate means slidingly connecting the adjacent ends of the rim sections for relative longitudinal adjustment, and means disposed interiorly of said rim and operable to effect a predetermined transverse adjustment of the rim sides when the rim sections are longitudinally adjusted.

3. A sole pattern having a pliant rim for fitting around a sole and made up of a front portion and a rear portion connected together for relative longitudinal adjustment, and means interiorly of said rim for retaining it in adjusted form and automatically operable by a relative longitudinal adjustment of the front and rear portions to effect a predetermined transverse adjustment of the rim sides.

4. A sole pattern having a pliant rim for fitting around a sole, said rim comprising a plurality of sections connected together for longitudinal adjustment, a plate carried internally of the rim by each section thereof, a portion of said plates being slotted, and means connecting said several plates and coöperating with the slots therein to permit an adjustment of the rim, and means for securing said plates in adjusted relation.

5. A sole pattern having a rim of pliant material for fitting around the edge of a sole, said rim having two opposed front sections connected together for relative longitudinal adjustment at the front ends thereof and having two opposed rear sections

connected for relative longitudinal adjustment to the rear ends of the respective front sections, a plate projecting inward from each section, pin-and-slot connection between the forward end portions of the front section plates to permit relative transverse adjustment thereof, pin-and-slot connection between the rear end portions of the rear section plates to permit relative transverse adjustment thereof, pin-and-slot connection

between all of said plates at their adjacent end portions to permit relative transverse adjustment of the rear end portions of the front section plates and transverse and longitudinal adjustment of the rear section plates relative to the front section plates, and means for locking the plates in adjusted relation. 15

In testimony whereof, I have hereunto signed my name to this specification.

JOHN H. GEIER.
